UNITED STATES PATENT OFFICE.

GEORGE W. KING, OF MARION, OHIO.

EXCAVATOR.

SPECIFICATION forming part of Letters Patent No. 655,784, dated August 14, 1900.

Application filed May 17, 1897. Serial No. 636,837. (No model.)

To all whom it may concern:

Be it known that I, GEORGE W. KING, of Marion, Marion county, Ohio, have invented certain new and useful Improvements in Excavators; and I do hereby declare the following to be a full, clear, and exact description of the invention, such as will enable others skilled in the art to which it pertains to make and use the same.

10 My invention relates to a machine designed for excavating and elevating or transferring mineral-bearing earth.

15 My invention relates more especially to an excavator having its car or body portion provided with the following: a suitably-operated shovel, an incline supported from the body portion and provided with a suitable track, a car mounted upon said track, apparatus for propelling said car upon said track, and the 20 arrangement of parts being such that said car when it is at the lower end of the track-bearing incline shall be in position to receive the material from the shovel, and said car when in its elevated position at the upper end of 25 the incline shall be in position to deliver the material to the separator or washer.

25 My invention consists in certain novel features of construction and arrangement of parts hereinafter described, and pointed out 30 in the claims.

In the accompanying drawings, Figure I is a side elevation of a machine embodying my invention. This figure shows the machine mounted upon a track arranged longitudinally of the bottom of the cut that has been 35 made by the excavator. Fig. II is a front end elevation of portions of the machine, and this figure shows the boom swung laterally to one side, with the excavating-shovel in position 40 over the car that is mounted upon the incline and that is designed to receive the material from the bucket. Fig. III is a top plan of the body portion of the excavator and the incline that is mounted upon said body portion. Fig. IV is a rear end elevation, partly 45 in section, on line IV IV, Fig. I, of portions of the machine and shows the zigzag arrangement of sluices or riffles and shows also a pump for disposing of the refuse when it is 50 not desirable to allow said refuse to run upon the ground near the machine. Fig. V is a side elevation of said incline and shows the

car upon said incline in a dumping position and shows the upper end of the hopper that is designed to receive the material from said car and convey it into a revolving screen of the separating apparatus. Fig. VI is a rear elevation showing the rear trucks of the machine, the rocking bolster extending transversely over said trucks, and the portion of 55 the machine's body portion that rests upon the central portion of the bolster between stops that are formed upon the bolster and prevent endwise displacement of the bolster.

Referring to the drawings, A designates the 60 car or body portion of the excavator, which body portion is provided with trucks A', that are mounted upon track-rails A², arranged longitudinally of the bottom of the cut a made by the machine and in which the ma- 70

chine operates.

B represents the laterally-swinging boom with which the forward end of the machine is provided. Said boom extends upwardly and outwardly from its lower pivotal center b, and at its upper end has attached a rod b', that at its inner end terminates in a sleeve b², that is mounted upon a vertical pin or bearing C', formed upon the upper end of the so-called "A-frame" or upwardly-extending frame C 80 and constituting the upper pivotal center of the boom. Apparatus for swinging the boom laterally is so well understood by those skilled in the art that a description thereof or further reference thereto is unnecessary in this specification. The boom is provided with an excavating-shovel B' and apparatus for thrusting the shovel in and out and apparatus for raising and lowering the shovel. The shovel-actuating apparatus is also so well understood by those skilled in the art that illustration or description thereof in this application is not required.

In the upper and rear portion of the car or body portion of the machine is suitably supported a revolving screen D, that is arranged longitudinally of the machine, declines toward its rear end, and extends somewhat rearward of the body portion. A hopper E is provided at the forward end of this screen and is arranged to convey the material received thereby into the forward end of the screen. The mineral-bearing earth is conveyed from the excavating-bucket to and dumped into

said hopper, and thence passes into the revolving screen. The coarser material that is too large to pass through the meshes of the screen passes out at the rear end of the screen onto 5 a rearwardly-declining apron G, that is arranged to receive the material from the rear end of the screen and deposit the same in a pile H at the rear end of the machine, as shown in Fig. I. The water, mineral, and 10 finer material that pass through the meshes of the screen fall in the main or entirely upon an inclined apron I, arranged below the forward and central portions of the machine. In the case illustrated in Fig. I another apron 15 I', that can be dispensed with, if desired, is arranged below the rear portion of the screen. Apron I' declines forwardly and the forward apron I declines rearwardly. The inclined aprons I I' are separated at their lower or dis- 20 charging ends to accommodate the escape of the material passing down said aprons onto the upper riffle or sluice of a series of riffles or sluices J, that are arranged in a zigzag form, as shown very clearly in Fig. IV. The 25 gold or valuable minerals are caught upon or held by these riffles or sluices, and the water or residue is caught in a basin K, formed at the foot of the lowermost riffle or sluice, and the water and refuse are forced by means of a 30 pump L through a pipe or conductor l to a point that is out of the way. This pump may be dispensed with if natural drainage can be had. The arrangement of sluices or riffles is such that the lower end of each riffle or sluice 35 above the lowermost sluice or riffle will discharge any matter escaping therefrom upon the upper end of the sluice or riffle next below.

An incline M is at its outer end seated 40 upon and arranged diagonally of the roof A⁴ of the car or body portion. The upper portion of this incline comprises a frame M', arranged horizontally and diagonally of and resting upon the roof of the body portion. 45 This frame M' supports a horizontally-ar- ranged or approximately horizontally-ar- ranged track M², whose rails extend longitudinally of the forward portion of said frame and at their forward ends join and form a 50 continuation of the rails of the inclined track m², that extends laterally of and downwardly from the roof of the car and is formed upon the inclined frame m, that correspondingly extends laterally of and downwardly from the 55 car's roof and is hinged or pivoted hori- zontally at its upper end, as at m', to the forward ends of the horizontally-arranged frame M'. The hinging of the inclined frame m to the horizontally-arranged frame not only accom- 60 modates the swinging of said inclined frame downwardly or upwardly and rearwardly out of the way, as may be desired in the transportation of the machine, but enables said inclined track-bearing frame to accom- 65 modate itself to any unevenness or height variation of the bank or ground, by which said portion of the incline may be supported

in the operation of the excavator. Said at- tachment of the lower portion of the incline to the incline's upper portion accom- 70 modates also the detachment of the former if said detachment for any reason becomes desirable. Frame m at its outer end is pro- vided, preferably, with a runner m³, that is arranged to rest upon the bank a' at the ad- jacent side of the cut, as shown in Figs. I and II, which runner is arranged longitudinally of the bank and accommodates the movement of the incline with the excavator as required from time to time during the ex- 75 tension of the excavation or cut. The incline comprises, furthermore, another inclined frame M³, that extends upwardly and rear- wardly from the upper end of the inclined track-bearing frame m over and is suitably 80 supported from the horizontally-arranged frame M'. A track M⁴ is formed upon the forward portion of said frame M³. Said track M⁴ has its two rails arranged alongside of the different rails, respectively, of track M². A 85 car N is arranged to move upon the aforesaid tracks. Said car, when it is upon the lower end of inclined track m², is in position to receive the contents of the excavating-bucket when the latter is hoisted and moved over 90 said car in said position of the car.

The track m², at its lower or outer end, is provided with stops m⁴, designed to be en- gaged by the wheels N' of the outer end of the car N when the latter is in position at the 100 bottom of the incline, and thereby prevent said car from running downwardly off the in- cline. The treads of the wheels N² at the in- ner or discharging end of car N are just wide enough to properly engage the rails of tracks 105 m² M² and are not wide enough when moved from track m² onto track M² to engage track M⁴. The treads of wheels N' of the car are, however, wider than the rails of track m² and extend laterally of said rails far enough to 110 cause them to run upon the rails of track M⁴ during the ascent of the car upon the incline, so that when the laden car is moved upwardly to the place at which it is in position to dump into the aforesaid hopper said wheels N' will 115 run upon track M⁴, while the car's wheels N² will move upon track M², so that the car will be stood upon its discharging end, as shown in Fig. V, and thereby dump or discharge its 120 contents into the hopper below through an opening A³ (shown in Fig. III) in the roof of the car. The discharging end of car N is pro- 125 vided, preferably, with a gate N³, that is automatically opened, as will hereinafter fully appear, when the said car is pulled to the place at which it is dumped.

The machine is provided with a brace O, employed in supporting the outer portion of the incline when bank a' is too low or rough for the runner. Said brace rests at one end 130 (see Figs. I and II) against the floor or lower part of the body portion A of the machine and engages at its opposite end the under side of the outer and lower end of the incline. A

cable O', attached at one end to the outer end of the incline and attached at its opposite end to the adjacent portion of the forward end of the roof of body portion A, prevents 5 lateral displacement of the incline.

- The apparatus employed for propelling the car N upon the incline comprises, preferably, a cable P, that at one end is attached to the central portion of a bail n, that straddles 10 car N and is horizontally pivoted at its ends to the outer end of the car. Cable P leads from said bail upwardly and rearwardly to and over a vertically-arranged sheave P', suitably supported from the upper end of the 15 rear portion of inclined frame M³, thence leads to and over a vertically-arranged sheave P², suitably supported below the roof of car A, and thence leads to a suitably-operated winding-drum P³, that in the case illustrated is 20 suitably supported within the forward portion of car A. Drum P³ in the case illustrated is loosely mounted upon a suitably-driven shaft Q, that is arranged horizontally and transversely of car A and is provided 25 with a driving-wheel Q'. A clutch for establishing operative connection between said drum and shaft is provided. One member Q² of this clutch is operatively and slidably mounted upon the shaft, and the other clutch 30 member Q³ is rigid with the drum. By sliding, therefore, the movable clutch member into operative connection with the stationary clutch member the drum is operatively connected with the shaft and rotated as required 35 to wind up the cable, and thereby propel the car N up the incline. Movement of said car in the opposite direction is effected by gravity upon interrupting operative connection between the drum and shaft. A sprocket-wheel 40 Q⁴ is operatively mounted upon said shaft and connected by means of a chain Q⁵ with a sprocket-wheel R', that is operatively mounted upon a horizontally-arranged shaft R, located and suitably supported rearwardly of 45 shaft Q. Shaft R is intergeared, as at R², with another suitably-supported shaft R³, that is arranged longitudinally of the machine, and a pinion R⁴, operatively mounted on the rear end of said shaft R, meshes with 50 an annular gear D', formed externally of and operatively connected with the revolving screen. Hence motion is communicated to the screen from the same shaft that is instrumental in the propulsion of car N. Gate N³ 55 of car N is attached, it will be observed, to the forward end of bail n and has the arrangement required to render it capable of closing the car's discharging end when the car is upon the lower portion of the incline. 60 The bail is and remains in the line of the engaging propelling-cable during the car's movements, and hence said gate is removed from the car's discharging end, as shown in solid lines, Fig. V, when the car's discharging end is 65 lowered relative to the car's opposite end, to which the bail is attached.

A machine of the character indicated is be-

lieved to be quite novel in the art, and its merits will readily be appreciated by those skilled in the art of excavating mineral-bearing earth.

A system of water-supply pipes W is arranged to convey water into the upper end of hopper E and onto the upper end of apron I.

A brake (not shown) would of course likely 75 be employed to hold or assist in holding car N in its dumping position; but the application of braking devices is so well understood that illustration thereof or further reference thereto is not here considered necessary. 80

I would also remark that a vertically-rocking bolster S extends transversely over the rear trucks of the machine between two cross-beams A⁵ A⁶, secured to and extending transversely of the bottom of the car-body, (see 85 Figs. I and VI,) and the rocking capability of the bolster enables the bolster to accommodate itself to any unevenness in the tracks upon which the machine is mounted. The trucks are connected and rendered movable 90 with the bolster in any approved manner, and interposition of the bolster between beams A⁵ and A⁶ renders it movable with the car-body. This bolster is shown very clearly in Fig. VI, and in dotted lines in this figure is shown 95 the manner in which said bolster can tip. The car-body or house or body portion of the machine is provided upon its under side with a depending member or portion A⁷, that upon its under side is convex transversely of the 100 machine and rests upon the central portion of the aforesaid bolster. Said depending portion of the car-body or house is therefore convex longitudinally of the bolster, and the latter can rock vertically upon said convex 105 surface. The bolster is provided with two upward projections S' S', arranged at opposite sides, respectively, of said depending convex member of the house or car-body, and constituting stops that prevent endwise displacement of the bolster.

What I claim is—

1. In an excavator of the character indicated, the suitably-supported incline extending downwardly and outwardly from the machine's body portion, and a cable O' attached at one end to the outer and lower end of the incline, and attached at its opposite end to the body portion, substantially as shown, for the purpose specified.

2. An excavator of the character indicated having its body portion provided with an incline or elevator that is supported, at its inner end, from the body portion and has its outer end provided with a runner, substantially as set forth.

3. In an excavator, the combination with the machine's body portion and the suitably-supported laterally-swinging boom provided with a suitably-operated excavating-shovel: 130 of an incline supported from and extending laterally of and downwardly from the body portion, and provided, at its outer end, with a runner arranged longitudinally of the ma-

chine, a car movable upon the incline, means for propelling the car upon the incline, a hopper arranged to receive the material from the car when the latter is dumped at the upper portion of the incline.

4. The combination with the excavator's body portion provided with an incline extending laterally of and downwardly from the body portion, and a car movable upon the incline: of a suitably-operated shaft Q supported from the body portion, a winding-drum loose upon said shaft, a clutch for establishing and interrupting operative connection between the drum and shaft, a cable 15 engaging said drum and operatively connected with the aforesaid car, and sheaves for guiding said cable, substantially as and for the purpose set forth.

5. The combination with the machine's body portion having an incline extending outwardly from the body portion, a car mounted upon said incline, said car having a bail straddling and pivoted to the sides of the car, means for tilting the car's discharging end 25 downwardly when the car is upon the upper portion of the incline, a suitably-actuated cable operatively connected with said bail and a gate attached to the bail and arranged to close the car's discharging end when the 30 latter is upon the lower end of the incline, substantially as and for the purpose set forth.

6. An excavator having its car-body provided, at each end, with two trucks arranged a suitable distance apart; a bolster extending over the trucks of the rear pair of trucks,

and arranged transversely of and below the car-body, which bolster has such connection with the trucks and car-body as to render the trucks and car-body movable together; a member depending from and rigid with the 40 car-body and resting upon the central portion of the bolster, which member has its lower surface convex transversely of the body portion, and two stops S' and S' arranged at opposite ends, respectively, of the aforesaid convex surface, substantially as shown, for the purpose specified.

7. An excavator having its car-body provided, at each end, with two trucks arranged a suitable distance apart; a bolster extending over the trucks of the rear pair of trucks and arranged transversely of and below the car-body, and having such connection with the trucks as to be movable with the latter; two beams A⁵ and A⁶ rigid with the car-body 55 and arranged at opposite sides, respectively, of, and in close proximity to, the bolster, and a member rigid with and depending from the car-body between the beams and resting upon the central portion of the bolster, which depending member has its lower surface convex transversely of the car-body, substantially as shown, for the purpose specified.

In testimony whereof I sign this specification, in the presence of two witnesses, this 24th day of April, 1897.

GEORGE W. KING.
